UNITED STATES PATENT OFFICE.

CHARLES PATRICK MULHERIN, OF AUGUSTA, GEORGIA.

DESIGN FOR A COLLAR-BUTTONER.

SPECIFICATION forming part of Design No. 28,918, dated June 28, 1898.

Application filed June 3, 1898. Serial No. 682,494. Term of patent 14 years.

To all whom it may concern:

Be it known that I, CHARLES PATRICK MULHERIN, a citizen of the United States, residing at Augusta, in the county of Richmond and State of Georgia, have invented a new and original Design for a Collar-Buttoner, of which the following is a specification.

In the accompanying drawings, Figure 1 is a face view of a collar-buttoner embodying my design; Fig. 2, an edge view thereof.

As shown in the drawings, the leading or material feature of my design consists of a collar-button hook having a stem which is flattened on opposite sides from a point near one end to the adjacent extremity, said flattened portion tapering continuously from the beginning of the flattened portion to an approximate point at the extremity and being bent at an obtuse angle with reference to the stem and curved into hook-shape to form a comparatively large throat, the opposite extremity of the stem being provided with a handle.

In the said drawings the numeral 1 designates the stem, which is flattened on oppo-

site sides from the point *a* to the extremity *b* of the stem. The flattened portion tapers continuously from the beginning *a* to the approximate pointed extremity *b*, as shown. The flattened portion from *a* to *b* is bent at 30° an obtuse angle to the body of the stem 1 and is curved into hook shape, as shown at 2, the extremity of the flattened and curved portion extending slightly inward toward the body of the stem and providing a comparatively 35 enlarged throat 3. The stem at its end opposite the hook-shaped portion is provided with a handle 4.

Having thus described my invention, what I claim as new, and desire to secure by Letters 40 Patent, is—

The design for a buttoner herein shown and described.

In testimony whereof I have hereunto set my hand in presence of two subscribing witnesses.

CHARLES PATRICK MULHERIN.
